UNITED STATES PATENT OFFICE

JOHN C. DUNER, OF CHICAGO, ILLINOIS, ASSIGNOR TO DUNER COMPANY, OF CHICAGO, ILLINOIS, A CORPORATION OF ILLINOIS

WATER CLOSET

Application filed July 1, 1929. Serial No. 375,243.

This invention relates to water closets provided for use in railway cars and like locations, and has for its object broadly the provision of a water closet particularly adapted for such use which will be so constructed and arranged that it will be sealed against updraft through the closet.

Toilets of this sort are ordinarily provided with a dump pan adapted to be dropped in flushing with resultant upflow of air frequently occurring with considerable velocity and producing a blast directed upwardly through the toilet or closet. This invention contemplates the provision of a closet having means for the elimination of such updraft and constructed and designed to protect its flushing by the sealing of the toilet or closet from upwardly or inwardly acting air currents.

A further object of the invention is the provision in a closet or toilet for use in railway cars and similar locations of improved means for sealing the toilet against updraft, which seals it before the dump pan is unseated and which is held in the sealed position until the dump pan has been reseated, the closet having generally the construction heretofore provided and operating in all respects as such toilets or closets have in the past.

A further object of the invention is the provision of simple and effective means for sealing a railway closet against upward air movement therethrough, automatically operative as an incident to normal use of the closet and which will not require the provision of parts or devices complicated in structure, expensive in character or requiring particular attention for operation or maintenance.

Numerous other objects and advantages of the invention will be apparent as it is better understood from the following description, which, taken in connection with the accompanying drawings, discloses a preferred embodiment thereof.

Referring to the drawings:

Figure 1 is a side elevation, parts being shown in section, of a railway closet embodying the present invention;

Fig. 2 is a view partially in front elevation

and partially in section, showing certain details of construction;

Fig. 3 is an enlarged sectional detail of a portion of Fig. 1;

Fig. 4 is a partial elevational view similar to Fig. 1 showing the relation of the parts in the position they assume at the beginning of the flushing or dumping operation;

Fig. 5 is an enlarged section taken substantially on the line 5—5 of Fig. 3, and

Fig. 6 is a sectional view similar to Fig. 5 showing the relation of parts in the position they assume at the beginning of the flushing or dumping operation.

For the purpose of illustrating the present invention, the drawings show a closet of the character generally provided in Pullman and railway cars. As shown on the drawings, this closet comprises an outer stand or support 11 of usual or preferred type which supports a closet bowl 12 at its upper end. This bowl is provided with an outlet 13 at its bottom, this outlet being normally closed by the water containing dump pan 14 which is pivoted upon a shaft 15, journaled as shown in Fig. 2 in opposite sides of the support 11. This shaft is provided with a rocker arm 16 fixed upon it to accomplish its oscillation and connected at 17 by means of an outwardly projecting stud 18 and cotter key 19 with a link 21 in turn connected to a flushing or dumping handle or lever 22.

Reference character 23 generally indicates the water supply for flushing and since this forms no part of the invention being here described will not be explained in detail. It may, however, be mentioned that raising the lever 22 swings the dump pan 14 from the position shown in Fig. 1 down and away from the closet bowl 12, this dump pan moving about the axis of the shaft 15. As an incident to this dumping, the flushing and valve mechanism 23 supplies water for the cleaning of the dump pan and for the provision of water in it after it has been returned by means of a suitable counterweight 24 to the usable or normal position shown in Fig. 1. The counterweight 24 is secured to the end of the shaft 15 opposite the arm 16 by means of a bolt 25, shown in Fig. 2.

It will be understood that the dump pan in moving from the position in Fig. 1 swings downward and to the left in a clockwise direction discharging its contents through a bottom opening 26 of the closet, and in such action provides for free upward air blast through such opening and through the closet.

The invention has for a general object the sealing against such upward air blast through the closet and to this end a closure 35 is provided which is adapted to be automatically arranged to close or seal the opening 26 through the bottom 24 of the closet before the dump pan 14 starts its movement from the closed position shown in Fig. 1. The closure or draft member 35 is fixed to or upon an arm 36 fixed to freely oscillating shafts 37 and 38 mounted in bearings 39 formed at or near the bottom of the closet support 11. The shaft 37 is provided with an arm 41 carrying an eccentric pin 42 arranged for engagement by parts movable with the dump pan in its dumping action, the construction preferably being such that the draft plate or member 35 is moved to close the opening 26 before the dump pan leaves its normal position and the member 35 remains in such closed position until the dump pan is returned to its sealing or original position.

An inwardly extending sleeve or hub portion 43 is the means for fixing the arm 16 upon the shaft 15 to accomplish the oscillation of the shaft as above mentioned, and as shown in Figs. 5 and 6. This sleeve or hub portion 43 encircles the end of the shaft 15 and is provided with an aperture or slot 44 for receiving the head of a rocker pin 45 carried in the shaft 15 so that the sleeve 43 may be rotated through an angle before the end of the aperture 44 engages the pin 45, causing rotational movement of the shaft 15 in dumping the dump pan 14 as an incident to the flushing of the closet. This initial movement of the sleeve 43 about the end of the shaft 15 moves the draft member 35 into and out of operative or sealing relation with the closet support by a mechanism which will now be described.

An arm 46 is fixed upon the sleeve 43 of the arm 16 by means of bolts 47 to oscillate with it and this arm carries an arcuate member or segment 48 being secured thereto by lock screw 49. The arcuate member or segment 48 is provided with a cam surface 51 adapted to ride over the offset pin 42, already mentioned, and hold the draft plate 35 in position to close the opening 26 through the closet. When the dump pan and the draft member are in normal position, the offset pin 42 is arranged in a recess 52 at the end of the arcuate or segmental member 48, the plate 35 being disposed without the influence of this part 48.

Viewing Fig. 4, it will be noted that immediately upon initial dumping movement

of the sleeve 43 of the arm 16 by the link 21 and handle 22, the arcuate member 48 presses down the pin 42 and swings upwardly and into closed or sealed position the draft plate 35, without moving or unseating the dump pan 14. It will be apparent also that further dumping movement of the handle 22 swings the pan 14 downwardly to the left, as shown by the broken lines in Fig. 4 and causes the outer cam face 51 to ride over this offset pin holding the draft plate 35 in closed position, the end of the aperture 44 engaging the pin 45 and imparting movement to the shaft 15 for opening the pan 14. The draft member 35 is formed with a heavy portion or counterweight 53 at its front to overbalance the draft plate or member 35 to move it and maintain it in the inoperative position shown in Fig. 1, and it will be understood of course that the initial dumping movement of the lever 22 acting upon the pin 42 lifts this counterweight and positively moves the draft plate 35 to the position shown in Fig. 4 where it is held thereafter by the action of the arcuate or segmental member 48 on the pin 42 caused by the dumping movement of the dump pan 14.

The closing of the draft member 35 and thereafter the dumping of the dump pan are accomplished by an upward pull on the hand lever 22, this being the action in the flushing of the closet. Thereafter the weight 24 returns the parts to normal position. I have provided means for insuring the movement of the draft plate 35 from the closing or sealing position shown in Fig. 4 after each return of the dump pan to its normal or receiving position, this movement occurring preferably after and only after the completion of the return movement of the dump pan. Upon return movement of the dump pan, the segmental member 48 slides over the offset pin 42 holding it in position to maintain the draft member 35 in the sealing or closed position until the end of the return movement of the dump pan 14. At the end of the movement of the dump pan the offset pin 42 enters the recess 52 and is thereafter immediately engaged by a hook member 54 integral with the arcuate or segmental member 48 to positively swing the draft member 35 to its non-obstructing position as illustrated in Fig. 1.

The counterweight or heavy portion 53 of the draft member tends to return the draft member 35 to this position and serves to hold it in such arrangement until subsequent flushing of the closet.

It will be noted that the valve mechanism 23 in flushing out the dump pan 14 delivers its contents to the draft member 35 together with the attendant flushing water which serves to cleanse this draft member upon its return to the non-closing position shown in Fig. 1 after use.

It is thought that the invention and many of its attendant advantages will be understood from the foregoing description, and it will be apparent that various changes may 5 be made in the form, construction and arrangement of the parts without departing from the spirit and scope of the invention or sacrificing all of its material advantages, the form hereinbefore described being merely 10 a preferred embodiment thereof.

I claim:

1. A water closet, comprising a closet bowl supported above its base, a dump pan positioned beneath the bowl and adapted to swing 15 from a sealing position downwardly to a dumping position, a draft member located beneath the dump pan and movable into a position sealing the outlet of the toilet, a cam having pivotal movement about the axis of 20 movement of the dump pan and for controlling the movement of said draft member, and a connection between said cam and said dump pan established at the end of the closing movement of said draft member for dumping 25 said dump pan.
2. A water closet, comprising a closet bowl supported above its outlet, a dump pan positioned beneath the bowl and adapted to swing from a sealing position downwardly 30 to a dumping position, said dump pan having a pivot member extending without the bowl, a draft member located beneath said dump pan and movable into a position sealing the outlet of the toilet, and a single cam 35 controlling the movement of said draft member and the movement of said dump pan, said member moving the draft member in advance of the movement of the dump pan.
3. A water closet, comprising a closet bowl 40 supported above its outlet, a dump pan positioned beneath the bowl and adapted to swing from the sealing position downwardly to a dumping position, a draft member located beneath the dump pan and movable into a position sealing the outlet of the toilet, a pivot member extending out from the dump pan and movable therewith, an arm secured for 45 pivotal movement with the draft member, a cam mounted for pivotal movement upon the pivot of said dump pan and engaging the arm of the draft member, and a pickup device between said cam and the pivot of said 50 dump pan for causing delayed opening movement of the dump pan upon flushing of the toilet.

JOHN C. DUNER.
